DAVID H. ATKINS, OF SAN FRANCISCO, CALIFORNIA, ASSIGNEE TO ATKINS, KROLL & CO., OF SAN FRANCISCO, CALIFORNIA, A FIRM.

TUBE-MILL.

1,125,921.

Specification of Letters Patent.

Patented Jan. 26, 1915.

Application filed February 11, 1914. Serial No. 818,031.

To all whom it may concern:

Be it known that I, DAVID H. ATKINS, a citizen of the United States, residing in the city and county of San Francisco and State 5 of California, have invented new and useful Improvements in Tube-Mills, of which the following is a specification.

This invention comprises improvements in the art of tube milling, which is, as at 10 present practised, a process for pulverizing and grinding ore by introducing this into a cylindrical or conical container, or a combination of both, revolving on its axis and charged with pebbles or balls. In passing 15 through this container, the ore is reduced in size by the impingement or grinding of the pebbles upon each other, or by the pebbles upon the lining of the interior of the mill or cylinder.

20 In the cylindrical mill, large and small pebbles arrange themselves at random. In the conical form of mill they arrange themselves naturally so that the largest pebbles occupy the greatest diameter and the smallest 25 pebbles the smallest diameter, with the result that in the area containing the greatest superimposed weight there are least points of contact to the cubic foot, and in the area containing the least superimposed 30 weight, there are the greatest number of points of contact per cubic foot. To remedy these alleged defects, I have devised a tube mill which may be best described as a step-cone form, that is, divided into two or more 35 compartments, each of a different diameter; the larger pebbles being retained in the compartment of least diameter and the smaller pebbles passing or being fed to compartments of successively great 40 diameter.

Increased efficiency is claimed for this device owing to the fact that in the chamber containing larger pebbles the liner can be ribbed so as to attain in the center a cascade 45 of these larger pebbles which are more efficient as percussion agents, due to their greater weight and momentum, while in the chambers of greater diameter this cascading or falling of pebbles can be eliminated, if 50 desired, and the maximum abrasive action of the small pebbles be obtained by increase of points of contact. Where a fine, granular product is desired rather than an impalpable powder or slime, to obtain the maximum 55 rapidity of discharge, and to avoid the ne-

cessity of grinding the ore so fine as to enable it to be carried off by suspension only, apertures can be made in the plates forming the ends of the chambers at varying distances from the circumference. Mixed pebbles can be introduced with the ore at the feed end of the mill and left to arrange themselves; or the larger pebbles can be introduced at the feed end of the mill and the smaller pebbles at the discharge end.

60 The invention consists of the parts and the construction and combination of parts as hereinafter more fully described and claimed, having reference to the accompanying drawing, in which the figure is a longitudinal central section through the device.

The mill is shown as having trunnion heads 2 and 3, open for the feed and discharge of ore and pulp respectively. The mill is preferably formed of, or with, a plurality of successive chambers 4, 5 and 6, of suitable length and of different diameters, as shown.

70 The principle involved in this invention is that, as the ore passes through the tube mill, a more rapid and effective grinding is accomplished when the pebbles or balls of greatest diameter are confined to the chamber of least diameter through which the ore must pass first, and as the pebbles decrease 75 in size they are allowed to pass to chambers of increasing diameter, thus increasing the number of points of abrasion as the ore particles are reduced in size and as the weight of the superimposed mass becomes greater. 80 It will be understood that where large balls or pebbles occupy a mill chamber or chambers, the interstices will be likewise large, and when smaller balls or pebbles occupy a chamber the interstices are likewise smaller 85

90 and the number of abrasive points of contact greater so that the imposed mass of grinding elements is far more effective upon the pulp passing between the small balls. Moreover, as the size of the pulp grain decreases, its 95 fracture is more readily effected and a small ball or pebble will be more economical than a large one under the circumstances. For this reason I have placed large balls or pebbles 7 in the chamber of least diameter, 100 small balls or pebbles 9 in the chamber of greatest diameter, and intermediate balls or pebbles 8 in the chamber of intermediate diameter. As the grinding proceeds the pulp passes from one chamber, as 4, into the 105 110

next chamber, as 5, through apertures 10. The dividing walls may be provided with central screens 12 to check the passage of the over-sized balls or pebbles from one chamber to another. From the chamber 5 the ground material passes through wall 13 to chamber 6 and thence out.

Having thus described my invention, what I claim and desire to secure by Letters 10 Patent is—

1. An apparatus for milling consisting of a horizontally disposed body having a relatively long end chamber, a middle chamber of less length and considerably greater diameter than said end chamber communicating with the latter, a second end chamber of less length and considerably greater diameter than said middle chamber communicating with the latter, balls in all of said 15 chambers, the balls in the middle chamber being of less diameter than the balls in the first end chamber and the balls in the second end chamber being of less diameter than the balls in the middle chamber, and 20 separate means for controlling each of the said communications between the chambers, which means retains the largest balls in the first end chamber and permits the smaller and smallest balls to enter the middle chamber. 25
2. An apparatus for milling consisting of 30

a body having a relatively long end chamber, a middle chamber of less length and considerably greater diameter than said end chamber communicating with the latter, a second end chamber of less length and considerably greater diameter than said middle chamber communicating with the latter, and 40 balls in all of said chambers, the balls in the middle chamber being of less diameter than the balls in the first end chamber and the balls in the second end chamber being of less diameter than the balls in the middle chamber. 45

3. An apparatus for milling consisting of a body having a series of intercommunicating chambers of successively increasing diameters and decreasing lengths and balls 50 of varying diameters in the respective chambers the balls in the chamber of least diameter having greater diameters than the remaining balls, the balls of least diameter being in the chamber of greatest diameter whereby to progressively increase the grinding points and aggregate weight of the balls in the respective chambers.

In testimony whereof I have hereunto set 55 my hand in the presence of two subscribing witnesses.

DAVID H. ATKINS.
